[57] CLAIM

The ornamental design for sport goggles, as shown and described.

DESCRIPTION

FIG. 1 is a front isometric view of sport goggles showing our new design.

FIG. 2 is a side elevational view of the sport goggles of FIG. 1.

FIG. 3 is a front elevational view of FIG. 1.

FIG. 4 is a rear elevational with a strap attached to the sport goggles of FIG. 1.

FIG. 5 is a rear elevational of the sport goggles of FIG. 1. FIG. 6 is a top plan view of the sport goggles of FIG. 1; and, FIG. 7 is a bottom plan of the sport goggles of FIG. 1.

The broken lines shown in FIGS. 1, 2, 4, 6 and 7 is for illustrative purposes only and forms no part of the claimed design.
